(57) **CLAIM**

The ornamental design for a combined ceiling fan blade iron and attachment unit, as shown and described.

DESCRIPTION

FIG. 1 is a perspective view from below of a combined ceiling fan blade iron and attachment unit in accordance

with my design, illustrating the environment of said combined ceiling fan blade iron and attachment unit;

FIG. 2 is an enlarged perspective view from below of the combined ceiling fan blade iron and attachment unit in accordance with my design, illustrating the environment of said combined ceiling fan blade iron and attachment unit;

FIG. 3 is a distal view of the combined ceiling fan blade iron and attachment unit in accordance with my design, illustrating the environment of said combined ceiling fan blade iron and attachment unit;

FIG. 4 is a side elevation view of the combined ceiling fan blade iron and attachment unit in accordance with my design, the opposite side being a mirror image of that shown illustrating the environment of said combined ceiling fan blade iron and attachment unit;

FIG. 5 is a bottom plan view of the combined ceiling fan blade iron and attachment unit in accordance with my design, illustrating the environment of said combined ceiling fan blade iron and attachment unit; and,

FIG. 6 is a top plan view of the combined ceiling fan blade iron and attachment unit in accordance with my design, illustrating the environment of said combined ceiling fan blade iron and attachment unit.

The broken lines showing environmental structure are for illustrative purposes and form no part of the claimed design.
